UNITED STATES PATENT OFFICE.

CLEUS GARRY, OF GRIFFIN, TEXAS.

OIL BURNER.

Application filed November 19, 1921. Serial No. 516,399.

To all whom it may concern:

Be it known that I, CLEUS GARRY, a citizen of the United States, residing at Griffin, in the county of Jefferson and State of 5 Texas, have invented a new and useful Oil Burner, of which the following is a specification.

This invention relates to oil burners, and more particularly to an oil burner 10 wherein steam is forced into direct contact with the oil at a point on the burner where the oil is burned, thereby converting the oil into a spray.

An object of the invention is to provide 15 a burner of this character having means to prevent the oil from leaking or dripping from the burner, when the same is not lighted.

Another object of the invention is to provide 20 means for controlling the passage of oil to the burner tip for regulating the blaze.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawing:—

35 The figure illustrates a vertical sectional view through a burner constructed in accordance with the present invention.

Referring to the drawing in detail, the valve includes a body portion indicated at 40 5 which is provided with a laterally extending pipe 6, formed integral with the body portion, which pipe is formed with an opening 7 at one end thereof to provide communication with the tip of the burner.

45 The tip includes a pipe 8 having internal threads to be positioned on the threaded connecting member 9, one end of the pipe 8 being tapered as at 10 to provide the tip proper. This member 9 is formed with a flange 11 which contacts with the extension 12 formed integral with the body portion 5, there being provided a connecting member 13 contacting with the flange 11 for securing the tip portion of the burner to 50 the body portion. As shown, the member 9 is of a diameter greater than the diameter

of the burner member 14 to provide a passageway therebetween, the burner member being of a length to extend to the tapered portion 10 of the pipe 8, where the same is 60 provided with inclined walls 15 conforming to the contour of the taper 10 so that the passageway between the pipe 8 and inclined walls 15, may be restricted to control the volume of steam passing therebetween. 65

Formed at the upper end of the burner member 14, is a recessed portion 16 adapted to accommodate the head 17 of the regulating valve 18, which supports a controlling wheel 19 by means of which the valve 70 70 may be moved towards and away from its seat, or recess portion 16. The valve 18 is threaded in the valve head 20 as at 21, there being provided a suitable collar 22 at the upper end of the head 20 for securing a 75 suitable packing on the head to prevent leakage between the head and valve member 18.

A securing collar 23 is threaded on the body 5 and has a flange cooperating with the flange 24 formed at the lower end of the head 20 for securing the head 20 to the body portion. Formed integral with the body portion is a lateral extension pipe 25 which may have communication with a suitable source of oil supply to direct the oil to the body portion 5 where the same may pass through the burner member 14 which is formed with a bore 26 extending throughout its length. 85

The valve member 18 is also formed with a longitudinal bore 27 which registers with the bore 26 and is designed to accommodate the rod 27 that passes through the valve and which is formed with a handle 28 at the upper end thereof, whereby the rod may be moved to clean the oil passageway and remove all foreign matter which may collect therein. It might be further stated that this rod also partially closes the oil passageway 100 to restrict the flow of oil therethrough and prevent the oil dripping from the burner. 90

In order that a fluid-tight connection will be had at the upper end of the valve, a gasket 29 is positioned at the upper end of 105 the valve member 18, which is held into position by means of the collar 30.

In the operation of the burner, oil is admitted to the body portion 5 through the lateral extension 25, the quantity of oil being regulated by means of the valve member 8. Steam is also admitted to the valve, 110

through the lateral extension 6, where the same contacts with the oil passing through the burner member 14, whereupon the oil is converted into a spray to be burned.

5 Having thus described the invention what is claimed as new is:—

An oil burner including a body portion, an elongated threaded member removably secured at one end of the body portion, a 10 burner tip having a threaded portion adapted to be positioned over the elongated threaded member and adjusted thereover, a burner member having a tapered extremity and having a longitudinal bore merging into 15 a recessed portion at one end of the burner,

an adjustable valve member having a head cooperating with the recessed portion to regulate the quantity of fuel passing through the burner member at a point within the body portion, means for supplying air to the 20 burner, and a rod extending through the valve member and burner member.

In testimony that I claim the foregoing as my own, I have hereto affixed my signature in the presence of two witnesses.

CLEUS GARRY.
